LARRY FITZGERALD, OF WHITTIER, CALIFORNIA.

UNDERREAMER.

1,017,743.

Specification of Letters Patent. Patented Feb. 20, 1912.

Application filed April 15, 1911. Serial No. 621,279.

To all whom it may concern:

Be it known that I, LARRY FITZGERALD, a citizen of the United States, residing at Whittier, in the county of Los Angeles, State 5 of California, have invented new and useful Improvements in Underreamers, of which the following is a specification.

This invention relates to an under-reamer adapted particularly for use in oil wells and 10 the like and for drilling a hole beneath the lower end of the casing of the same or larger diameter than the outside diameter of the casing; the prime object of the invention being to provide an under-reamer of simple 15 and strong construction which may be manipulated both below the casing and within the casing without the necessity of going through special motions for "tripping" the cutters of the under-reamer, and so that the 20 under-reamer may be moved up into the casing and then lowered again to its working position without the necessity of tripping as in a number of other devices.

Considered broadly, the structure embodying 25 my invention consists of a mandrel in combination with two pivotally carried cutters, and spring means for forcing the cutters apart and stops to limit the outward movement of the cutters; combined with 30 shoulders and bearing faces for the support of the cutters when in their different positions.

The specific structure of my under-reamer will be best understood from the following 35 specification and the accompanying drawings, in which—

Figure 1 is a view showing my under-reamer in elevation, and in its drilling position in a well. Fig. 2 is a longitudinal section 40 of the lower portion of the reamer, showing the cutters in their closed position, and illustrating the clamp used for holding the cutters in that position when the under-reamer is outside the casing. Fig. 3 is a partial side elevation of the lower portion of the mandrel. Fig. 4 is a partial side elevation 45 of the upper portion of one of the cutters. Fig. 5 is a cross section taken on line 5—5 of Fig. 1.

In the drawings 5 designates the body of 50 a mandrel which may be made of any size, proportions and design, having a screw threaded pin 6 on its upper end for connection with a stem (as is usual with drilling tools). Mandrel 5 carries a centrally positioned 55 downwardly extending tongue 7

which is of the configuration shown in Figs. 2 and 3. Below the body of the mandrel, tongue 7 is wedged shape, viewed as in Figs. 1 and 2, with its opposite surfaces either 60 straight or slightly curved as illustrated. These opposite surfaces 8 are extended upwardly into the body of the mandrel as at 9, forming the bottoms of recesses 10 which are cut in opposite sides of the mandrel immediately above the tongue 7. In the lateral walls 11 of these recesses 10 are cut grooves 65 12 for the reception of supporting pins 13 on the upper ends of cutters 14.

Cutters 14 are formed as is best illustrated 70 in Figs. 2 and 5, being of such longitudinal section as to rest against surfaces 8 and 9 when the cutters are drawn in toward each other. The lower ends of the cutters are formed in any ordinary or preferred manner 75 for efficient drilling. Each of the cutters is supported pivotally at its upper end by a pin 13 in grooves 12. At the upper end of each cutter is a shank portion 15 which fits into recess 10; and immediately below shank 80 15 the cutter is enlarged, presenting a shoulder 17 which bears against lower end surface 18 of the mandrel. The cutters are also extended around tongue 7 so as to form a sort of groove in the inner surfaces of the 85 cutters, the bottom 20 of the groove bearing against surfaces 8 of tongue 7 when the cutters are closed.

Springs are utilized to force the cutters apart, and these springs are preferably arranged as shown in Fig. 2. Through the lower end of tongue 7 a bore 25 is cut in which a heavy spring 26 is housed within two cylindrical protective casings 27. Spring 26 is a compression spring and tends 95 to press outwardly against shoulders 28, thus tending to force the cutters apart. A jointed bolt 29 passes through the spring from one cutter to the other, and this bolt may or may not be used as a stop for the movement of the cutters apart from each other. I have shown the bolt provided with a sliding loop joint, this joint providing for the movement necessary to separate and contract the cutters. The bolt is provided with 100 heads 30 which bear against shoulders 31 and thus act as stops to the outward movement of the cutters. Plugs 32 cover the outer ends of the bolts. Above the spring arrangement just described, and located in 105 the lower end of the mandrel body directly above tongue 7, is a second spring 35 which

presses outwardly against the inner faces of shanks 15 of cutters 14. A bolt 36 passes through spring 35 and is preferably provided with heads 37 on its ends which act in conjunction with shoulders 38 as stops to the outward movement of the cutters. Spring 35 is preferably of lesser strength than spring 26, but not necessarily so. The main stop for limiting the outward movement of the cutters is provided in a pin 40 which extends through the upper part of tongue 7, projecting on each side of the tongue. Extensions 41 having slots 42 therein are made on cutters 14, the slots encompassing pin 40 and allowing the cutters to move outwardly as far as illustrated in Fig. 1. The other stops previously described also allow a movement to this position and no farther; and, although the outward movement of the cutters is sharply limited, the cutters hang loosely at all points from the mandrel—there are no solid connections which are liable to be broken by excessive strain.

When the under-reamer is out of the well, the cutters may be held in their closed positions by means of such a clamp as is illustrated at 50 in Fig. 2. This clamp is composed of a band 51 (preferably provided with a joint so as to be placed around the under-reamer before being withdrawing from the casing) and a screw 52 adapted to act against one of the cutters and to thereby force the cutters together. The lower ends of the cutters are placed in the casing and the clamp removed. The under-reamer may then be lowered through the casing to the bottom of the well, the cutters being held closed by the casing until the under-reamer emerges from the lower end of the casing. The springs then cause the cutters to immediately expand to their working position. The cutters will be kept expanded until it is desired to move the reamer from the well. When the reamer is pulled upwardly the contact of the outer faces of the cutters with the shoe on the lower end of the casing will cause the cutters to be forced together, and the cutters will be so held by the casing until they emerge from the upper end. On account of the long gradual slope on the outer faces of the cutters, it will be seen that they are quite easily forced inwardly by an upward pull on the under-reamer; the springs expanding the cutters may be extremely strong, and still the cutters may be easily forced inwardly when pulled upward into the casing. If it is desired to lower the under-reamer again this can be done without the necessity of raising it to the top of the well, as the reamer is always in condition to expand when let below the casing. Thus, with my reamer, drilling can be done immediately beneath the lower end of the casing; so close that the cutters enter the casing on

the upper part of each stroke. This cannot be done with the ordinary reamer as the cutters therein are only closed by great upward pressure against the casing.

Having described my invention, I claim:—

1. An under-reamer, comprising a mandrel, a tongue projecting centrally from the lower end of the mandrel and of smaller size than the mandrel so as to form downwardly facing shoulders, there being recesses in the mandrel directly above opposite sides of the tongue, cutters loosely pivoted to the mandrel with their upper portions in said recesses, the lower portions of the cutters being enlarged to present upwardly facing shoulders which bear against the downwardly facing shoulders of the mandrel, the lower inner portions of the cutters bearing against the tongue, spring means for expanding the cutters, a pin projecting from the tongue, and slotted extensions on the cutters and engaging the pin. 70 75 80 85 90

2. An under-reamer, comprising a mandrel, a tongue projecting centrally from the lower end of the mandrel and of smaller size than the mandrel so as to form downwardly facing shoulders, there being recesses in the mandrel directly above opposite sides of the tongue, cutters loosely pivoted to the mandrel with their upper portions in said recesses, the lower portions of the cutters being enlarged to present upwardly facing shoulders which bear against the downwardly facing shoulders of the mandrel, the lower portions of the cutters bearing against the tongue, a compression spring passing through the tongue and pressing outwardly against the cutters, a second compression spring arranged within the mandrel between the said recesses and pressing outwardly on the cutters, and stop means to limit the outward movement of the cutters and located on the cutters between the two springs. 95 100 105 110

3. An under-reamer, comprising a mandrel, a tongue projecting centrally from the lower end of the mandrel and of smaller size than the mandrel so as to form downwardly facing shoulders, there being recesses in the mandrel directly above opposite sides of the tongue, cutters loosely pivoted to the mandrel with their upper portions in said recesses, the lower portions of the cutters being enlarged to present upwardly facing shoulders which bear against the downwardly facing shoulders of the mandrel, the lower inner portions of the cutters bearing against the tongue, a compression spring passing through the tongue and pressing outwardly against the cutters, a second compression spring arranged within the mandrel between the said recesses and pressing outwardly on the cutters, and stop means to limit the outward movement of the cutters and located on the cutters be- 115 120 125 130

tween the two springs, said stop means comprising a pin projecting from the side of the tongue and slotted extensions from the cutters and engaging the pin.

- 5 4. An under-reamer, comprising a mandrel, a pair of cutters loosely pivoted at their upper ends to opposite sides of the mandrel, a compression spring between the cutters and pressing outwardly against them, a second compression spring arranged 10 between the cutters below the first mentioned compression spring and pressing outwardly on the lower part of the cutters, and stop means to limit the outward movement 15 of the cutters and located on the cutters between the two springs.
5. An under-reamer, comprising a mandrel, a tongue projecting centrally from the lower end of the mandrel and of smaller 20 size than the mandrel, cutters loosely piv-
- oted to the mandrel at their upper ends and on opposite sides of the tongue, a compression spring passing through the tongue and pressing outwardly against the cutters, another compression spring arranged between 25 the cutters and pressing outwardly on them, the second mentioned compression spring being below the first mentioned compression spring, and stop means to limit the outward movement of the cutters away from the 30 mandrel and located between the two springs.

In witness that I claim the foregoing I have hereunto subscribed my name this 5th day of April 1911.
